CLAIM

We claim the ornamental design for a handheld television/internet remote control, as shown and described.

DESCRIPTION

FIG. 1 is a perspective view showing the top, rear and right sides of our handheld television/internet remote control;

FIG. 2 is a top view thereof;

FIG. 3 is a top view thereof in an open position;

FIG. 4 is a right side view thereof in a closed position;

FIG. 5 is a left side view thereof in a closed position;

FIG. 6 is a front end view thereof in a closed position;

FIG. 7 is a front end view thereof in an open position;

FIG. 8 is a rear view thereof in an open position;

FIG. 9 is a rear view thereof in a closed position;

FIG. 10 is a cross sectional view taken along line 10—10 of

FIG. 3; and,

FIG. 11 is a bottom view thereof.
